US00D996250S

(12) **United States Design Patent** (10) **Patent No.:** **US D996,250 S**
(45) **Date of Patent:** **** Aug. 22, 2023**

(54) **DOOR OR WINDOW MAGNETIC SENSOR**

(71) Applicant: **HANGZHOU EZVIZ SOFTWARE CO., LTD.**, Hangzhou (CN)

(72) Inventors: **Chongkun Huang**, Hangzhou (CN);
Weike Zhu, Hangzhou (CN)

(73) Assignee: **HANGZHOU EZVIZ SOFTWARE CO., LTD.**, Hangzhou (CN)

(**) Term: **15 Years**

(21) Appl. No.: **29/782,896**

(22) Filed: **May 10, 2021**

(30) **Foreign Application Priority Data**

Nov. 9, 2020 (CN) 202030673650.9

(51) **LOC (14) Cl.** **10-05**

(52) **U.S. Cl.**

USPC **D10/106.6**

(57) **CLAIM**

The ornamental design for a door or window magnetic sensor, as shown and described.

DESCRIPTION

FIG. 1 is a front elevation view;

FIG. 2 is a back elevation view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1; and,

FIG. 7 is a perspective view of FIG. 1.
